(57) **CLAIM**

The ornamental design for a tray for keyboard and trackpad, as shown and described.

DESCRIPTION

FIG. 1 is a top side view of a tray for keyboard and trackpad; FIG. 2 is a bottom side view of a tray for keyboard and trackpad;

FIG. 3 is a front view of a tray for keyboard and trackpad;

FIG. 4 is a back view of a tray for keyboard and trackpad;

FIG. 5 is a left side view of a tray for keyboard and trackpad;

FIG. 6 is a right side view of a tray for keyboard and trackpad;

FIG. 7 is an isometric view of a tray for keyboard and trackpad showing the top, left, and back sides; and,

FIG. 8 is an isometric view of a tray for keyboard and trackpad showing the front, bottom and right sides.

Broken lines shown in the drawings illustrate portions of the tray and form no part of the claimed design.
